DESIGN FOR A FOOD WRAPPER

Anna Kulander, Detroit, Mich.

Application January 27, 1934, Serial No. 50,522

Term of patent 7 years

To all whom it may concern:

Be it known that I, ANNA KULANDER, a citizen of the United States, residing at Detroit, in the county of Wayne and State of Michigan, have invented a new, original, and ornamental Design for a Food Wrapper, of which the following is a specification, reference being had to the accompanying drawing forming part thereof.

The figure is a plan view of a wrapper showing my new design.

I claim:

The ornamental design for a food wrapper, as shown.

ANNA KULANDER.
